UNITED STATES PATENT OFFICE.

EVERETT H. BARNEY, OF SPRINGFIELD, MASSACHUSETTS.

SKATE.

SPECIFICATION forming part of Letters Patent No. 274,254, dated March 20, 1883.

Application filed January 19, 1883. (No model.)

To all whom it may concern:

Be it known that I, EVERETT H. BARNEY, a citizen of the United States, residing at Springfield, in the county of Hampden and State of Massachusetts, have invented new and useful Improvements in Skates, of which the following is a specification.

This invention relates to an improved construction of devices for operating the clamping mechanism of skates, whereby the latter are secured to and disengaged from the sole and heel of a boot.

One feature of my invention relates to improvements in means for imparting the requisite motion to the sole and heel clamps of a skate and for forcing said clamps against the heel and sole of a boot and retaining said clamps in a locked position.

A second feature of my invention relates to improved means for connecting the screw-rod of a skate with the heel-clamp thereof.

A third feature of my invention relates to improvements in the construction of the heel-clamp and the heel-clamp-supporting parts of the skate.

In the drawings forming part of this specification, Figure 1 is a side elevation, and Fig. 2 is a bottom plan view, of a skate embodying my improvements. Fig. 3 illustrates the rear end of the screw-rod. Fig. 4 is a rear elevation, and Fig. 6 is a bottom plan view, of the heel-clamp. Fig. 5 is a plan view of the nut-link. Fig. 7 is a top plan view, a side elevation, and a bottom plan view of the rotating crank-stud. Fig. 8 is a plan view of the lever. Fig. 9 is a bottom plan view of the heel-plate and one cheek-piece, and Fig. 10 is an end view of the same.

The metallic sole-plate A is secured to the runner c by metallic brackets in the usual way, as shown. Two clamp-studs, m m, having T-shaped heads whose arms lie in a line with the runner c, are secured to said sole-plate with said heads projecting downward beneath said plate.

The sole-clamps b b consist of two metallic straps reaching from a point just back of the sole-plate toward the toe of the skate, and, curving outward beyond the edges of the sole-plate, their ends are turned upward at right angles to the plane of the sole-plate to form clamp-hooks or dogs, as shown, to bear against

the opposite edges of the sole of the boot and clamp the latter between them. Said sole-clamps are provided with curved slots, as shown, which permit of placing them over the said heads of the studs m m, when they are so held as to bring the parallel sides of said heads in line with the opposite edges of said slots, and then by turning said clamps to bring their rear ends together said heads stand across said slots, thereby holding them up under the sole-plate and permitting them to so slide thereon as to allow the outer ends of the clamps to move toward and from the edges of the sole-plate. The rear ends of the clamps b b are perforated and fitted to receive therethrough a cylindrical stud or pivot forming a connection common to the rear ends of both clamps. Said stud or pivot is illustrated in three positions in Fig. 7, and is designated as a rotating crank-stud. The said crank-stud e has a cylindrical head, 5, a cylindrical body, 4, whose circumferential surface is concentric with the border of said head, and the end 3 of which is milled off on opposite sides thereof, as shown, and is tapped to receive a screw, f. A crank-pin, x, is provided on said rotating stud e, and when the latter is in place through the perforated rear ends of the sole-clamps the said ends have a bearing on the said cylindrical body part 4 of said crank-stud. The lever h, having a slot therethrough conforming to the shape of the milled end 3 of the said stud e, is secured to the latter by the screw f, so that when the said clamps, stud e, and lever h are united in operative relation they constitute the mechanical structure which those parts represent in Figs. 1 and 2.

A nut-link, o, having its nut end tapped to receive the screwed end of the screw-rod n, is perforated to receive through its flat portion the crank-pin x on the stud e, and is suitably secured thereon by riveting or otherwise to unite it thereto, but loosely enough to permit said stud to be freely turned.

The metallic heel-plate v is provided with an abutment, s, for the front side of the heel of the boot, and is attached to the rear end of the runner by two cheek-pieces, i i. Each of said cheek-pieces is fastened to the heel-plate v by riveting or other suitable means. As herein shown, each cheek-piece has a part on

its upper edge which projects through a slot, *y*, in said heel-plate, and is riveted upon the top side of the latter, and the lower edges of said cheek-pieces are bolted to the sides of the 5 runner, as shown. The form of said cheek-pieces is such that when they are united under the heel-plate, as aforesaid, they form a longitudinal chamber under the heel-plate, and each one is provided with a lip or projection, 10 *z*, standing out from its side and leaving a space between it and the heel-plate above, as shown. It is obvious that the heel-plate *v* and the two cheek-pieces *i i*, together with the parts *zz*, may, if desired, be all cast in a united 15 form in one piece.

The heel-clamp *w*, plan and end views of which are shown in Figs. 4 and 6, is slotted, as in Fig. 6, and is provided with upwardly-projecting spurs or dogs, as in Figs. 1 and 4, for engaging with the heel of the boot and with a cylindrically perforated and split lip, *d*. The heel-clamp is thus adapted to slide under the heel-plate *v*, astride of the cheek-pieces *i i*, the portions thereof each side of its slot 6 passing 20 between the lips or projections *zz* and the under side of the heel-plate, and when said heel-clamp is in place on the skate the said lip *d* stands before the rear end of the aforesaid 25 chamber under the heel-plate.

The screw-rod *n* forms an adjustable connection, operating in a direct longitudinal line between the heel and sole clamps of the skate, for uniting said clamps and for varying the 30 distance between the heel-clamps and rotating the crank-stud *e*. Said screw-rod enters the rear end of the nut-link *o*, extends from thence rearwardly through said chamber under the heel-plate, and has a groove, *7^a*, around it near its 35 rear end. The said lip *d*, by reason of its being split open at its lower edge, is capable of being sprung open to allow of placing its partly-separated parts within said groove *7^a*, and then closing said parts upon the rod *n*, whereby the heel-clamp is so directly connected to 40 said rod that any longitudinal movement of the latter causes a like movement of said heel-clamp. The said lip *d* is not so closely shut upon rod *n* but that the latter can be freely 45 turned by applying the fingers to the end thereof for adjusting the clamps of the skate, as above described.

The operation of my improvement is as follows: In Fig. 1 are shown the dotted outlines of the sole and heel of a boot, to illustrate the relation of the latter and the fastening devices of the skate, and to show the positions thereof when the latter is clamped to a boot. Fig. 2 illustrates the position of said fastening devices when the skate is unfastened and taken 50 off from the boot. As shown in both full and dotted lines in Fig. 2, the lever *h*, in being operated to fasten the clamps of the skate or to unfasten them, may be swung in either direction in a horizontal plane under the shank of the boot and over the clamp-connecting devices. The movement of the clamps of the skate 55 caused by turning the crank-stud *e* by lever *h*

may be to the extent of double the distance of the crank-pin *x* from the axial line of the said stud *e*. By, however, properly adjusting the 70 heel and sole clamps to bring them near to the heel and sole of the boot, by turning rod *n* before swinging lever *h*, as aforesaid, and then swinging the latter around to a central line, as in Fig. 1, the movement of said crank-pin from a point on either side of a central longitudinal line opposite the axis of the stud *e*, drawn through the skate from heel to toe, to the position shown in Fig. 1, which brings it on said central line, serves to complete the fastening. Said adjustment having been made, the skate is applied to the boot, and lever *h* is swung around on a line with the rod *n* and the center of the nut-link *o*, thereby bringing the clamps forcibly against the sole and heel, the abutment *s* receiving the 80 force of the heel-clamp movement. Swinging the lever to the right or left under the boot unfastens the skate therefrom. Hence, since said lever may be swung either way, it is unnecessary to make right and left skates, as either 85 skate can with equal convenience be secured to either foot. This feature of construction results in considerable saving in the cost of manufacture. Said lever *h* is provided with the lips *7* on either edge thereof or other suitable device for causing it to be engaged with the adjacent operating devices of the skate when occupying the position shown in Fig. 1, whereby it is secured against being accidentally swung away from that position when the 90 skate is clamped. Said lever springs up slightly when one of said lips *7* encounters the said fastening-connections under it, letting said lip slip over the latter, bringing rod *n* between said lips.

In a separate application for Letters Patent I describe modified means for operating the heel and toe clamps by a lever capable of swinging to both sides.

What I claim as my invention is—

1. The combination of devices for clamping a skate to the heel and sole of a boot, substantially as described, with a rotating crank-stud connected with and located in a central line between said devices, and a lever connected 115 with said stud for fastening and unfastening, as set forth.

2. The combination of devices for clamping a skate to the heel and sole of a boot, substantially as described, with a rotating crank-stud connected with and located in a central line between said devices, and a lever connected with said stud for fastening and unfastening, adapted by means, substantially as described, to be engaged with the clamp-connections when swung into a line therewith, substantially as set forth.

3. The combination, with the rotatable screw-rod *n*, having a groove, *7^a*, around it, of the heel-clamp *w*, having the split lip *d* thereon, adapted to have its semi-divided portions engage in said groove, substantially as set forth.

4. The heel-plate *v*, the cheek-pieces *i i*, secured to said heel-plate and each provided with

the lip z , in combination with the heel-clamp w , having the lip d thereon, and the screw-rod n , all as set forth.

5. The combination, in a skate, of heel and sole clamps, substantially as described, with a rotating crank-stud pivoted in said sole-clamps, a nut-link pivoted to the crank-pin of said stud, a longitudinal rotatable screw-rod connected to said heel-clamps, and a lever for fastening 10 and unfastening connected with said crank-stud, having its free end movable in a horizontal plane in either direction from said screw-rod, all as set forth.

6. The combination, in a skate, of heel and toe clamps, and a tightening and releasing lever 15 connected by two pins to the separate clamping devices, and arranged, substantially as described, to tighten the clamps by carrying the lever to either side to bring the pin connected to the heel-clamp in front of the other pin-connection, substantially as set forth. 20
